CLAIM

I claim the ornamental design for a foldable display, as shown and described.

DESCRIPTION

FIG. 1 is a front perspective view of a foldable display showing my new design in which the foldable display is shown in a closed position;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a foldable display showing my new design in which the foldable display is shown in a fully open position;

FIG. 9 is a front view thereof;

FIG. 10 is a rear view thereof;

FIG. 11 is a left-side view thereof;

FIG. 12 is a right-side view thereof;

FIG. 13 is a top view thereof;

FIG. 14 is a bottom view thereof;

FIG. 15 is a front perspective view of a foldable display showing my new design in which the foldable display is shown in a partial open position;

FIG. 16 is a front view thereof;

FIG. 17 is a rear view thereof;

FIG. 18 is a left-side view thereof;

FIG. 19 is a right-side view thereof;

FIG. 20 is a top view thereof; and,

FIG. 21 is a bottom view thereof.

(Continued)

The broken lines in the figures depict portions of the foldable display which form no part of the claimed design.
